Primary Examiner — David Muller*(74) Attorney, Agent, or Firm* — Fitch, Even, Tabin & Flannery LLP(57) **CLAIM**

I claim the ornamental design for a suction handle, as shown and described.

DESCRIPTION

FIG. 1 is a perspective view of an ornamental design for a suction handle;

FIG. 2 is a second perspective view thereof;

FIG. 3 is a top plan view thereof;

FIG. 4 is a bottom plan view thereof;

FIG. 5 is a right side elevational view thereof;

FIG. 6 is a left side elevational view thereof;

FIG. 7 is a rear elevational view thereof; and,

FIG. 8 is a front elevational view thereof.

The broken lines depict unclaimed environmental subject matter and form no part of the claim.
